Primary Examiner — Daniel Bui(74) *Attorney, Agent, or Firm* — LaRiviere, Grubman & Payne, LLP**CLAIM**

(57) The ornamental design for a connector, as shown and described.

DESCRIPTION

FIG. 1 is a front perspective view of a connector, showing our new design;

FIG. 2 is a front view thereof;

FIG. 3 is a rear view thereof;

FIG. 4 is a side view thereof;

FIG. 5 is an opposing side view thereof;

FIG. 6 is an end view thereof;

FIG. 7 is an opposing end view thereof; and,

FIG. 8 is a side view thereof, in flexed condition.

The broken lines showing the environment in the Figures are for illustrative purposes only and form no part of the claimed design.
